CLAIM

The ornamental design for a packaging container, as shown and described.

DESCRIPTION

FIG. 1 is a perspective view of a packaging container, showing our new design.

FIG. 2 is a front view thereof.

FIG. 3 is a rear view thereof.

FIG. 4 is a top plan view thereof.

FIG. 5 is a bottom plan view thereof.

FIG. 6 is a right side view thereof.

FIG. 7 is a left side view thereof; and,

FIG. 8 is a sectional view taken along line 8-8 of FIG. 2. The broken lines are shown for the purpose of illustrating portions of the design that form no part of the claimed design.

1 Claim, 8 Drawing Sheets
